DESIGN FOR AN OVERBED UTILITY
CABINET

Garry Sands, Cleveland Heights, Ohio

Application July 5, 1947, Serial No. 140,128

Term of patent 3½ years

(Cl. D33—19)

To all whom it may concern:

Be it known that I, Garry Sands, a citizen of the United States, residing at Cleveland Heights, county of Cuyahoga, and State of Ohio, have invented a new, original, and ornamental Design for an Overbed Utility Cabinet, of which the following is a specification, reference being had to the accompanying drawing, forming a part thereof.

Fig. 1 is a perspective view of my overbed utility cabinet embodying my new design, the bed being indicated in broken lines for illustrative purposes only;

Fig. 2 is an end elevation of the same;

Fig. 3 is a plan view of the cabinet.

I claim:

The ornamental design for an overbed utility cabinet, as shown and described.

GARRY SANDS.
